J. SYLVAN,
RIDGE CONSTRUCTION FOR SKYLIGHTS AND THE LIKE,
APPLICATION FILED DEC. 8, 1920.

1,401,208.

Patented Dec. 27, 1921.

Inventor -
Joseph Sylvan
By Glenn E. Melholt Atty.

UNITED STATES PATENT OFFICE.

JOSEPH SYLVAN, OF CHICAGO, ILLINOIS.

RIDGE CONSTRUCTION FOR SKYLIGHTS AND THE LIKE.

1,401,208.

Specification of Letters Patent. Patented Dec. 27, 1921.

Application filed December 8, 1920. Serial No. 429,076.

To all whom it may concern:

Be it known that I, JOSEPH SYLVAN, a citizen of the United States, and a resident of Chicago, in the county of Cook and State of Illinois, have invented certain new and useful Improvements in Ridge Construction for Skylights and the like; and I do hereby declare that the following is a full, clear, and exact description thereof, reference being had to the accompanying drawings, and to the letters of reference marked thereon, which form a part of this specification.

This invention relates to improvements in ridge construction for skylights and the like, and consists of the matters hereinafter described and more particularly pointed out in the appended claims.

The primary object of the invention is to provide a flexible, water tight construction for connecting the adjacent margins of the swinging sections at the ridge of a skylight, which construction will adapt itself to accommodate for the swinging movement of said sections, and will be supported at all times, against collapse or distortion, no matter what the angular position of said swinging sections may be.

The many advantages of the invention will more fully appear as I proceed with my specification.

In the drawings:—

Figure 1 is a transverse section through the ridge part of a skylight, to which my improved ridge construction has been applied, and shows the swinging sections of the skylight in a closed position.

Fig. 2 is a view, on an enlarged scale, of the parts shown in the top end of Fig. 1, when said swinging sections are in a full open position.

Fig. 3 is a detail longitudinal section, taken on the line 3—3 of Fig. 1.

Referring now in detail to that embodiment of the invention illustrated in the accompanying drawings, 5—5 indicate the oppositely disposed rafters of a skylight which are inclined downwardly and outwardly from each other. Said rafters are spaced longitudinally of the skylight, and are connected together by angle bars 6, which extend the full length of said skylight. Upon said angle bars 6, are secured the top or inner ends of inverted T-shaped glazing bars 7, which extend parallel with the rafters, and on said glazing bars are supported the panels 8 of the skylight. Arising from the

junction of said rafters are posts 9 in the form of angle bars. Each post carries on its top end a bearing plate 10 having an eye 11 (see Fig. 3) in which is secured a short, stub shaft 12, extending longitudinally of the skylight in the plane of the ridge or peak thereof.

The space between the angle bars 6 is left open as shown, to provide communication between the room beneath the skylight and the outside atmosphere, when it is so desired. This space is normally closed by secondary skylight sections 13 and 14 which are pivoted on the short shafts 12, to swing transversely of the skylight to open and close the space between the angle bars 6 of the skylight. Each section comprises inner top and outer bottom longitudinally extending angle bars 15 and 16 which are connected together by transversely extending inverted T-shaped glazing bars 17, providing the support for the usual glass panels 18. To the inner top angle bars 15 are attached hinge straps 19, each of which has an eye 20 to receive and have bearings on the projecting ends of shafts 12 at the top ends of the posts 9. Preferably there is one strap on each side of the post strap 10, and pins 21 extend through the shaft at the ends of the eyes 20 to prevent endwise movement of the straps 19 on said shafts 12. The outer bottom angle bars 16 carry gutter strips 22, which, when said sections are in their closed position, engage upon the upstanding flange 90 of the angle bars 6, and catch such vapor as condenses on the panels 18. The opening and closing movement of said sections 13 and 14 may be brought about by any suitable means, but preferably I employ the means 95 for that purpose, shown in my copending application filed on November 4th, 1920, Serial No. 421,625.

To the other surfaces of those flanges of the angle bars 15, arranged at a right angle 100 to the panels 18, are secured thin sheet metal hinge strips 23—24, each of which terminates in an upwardly or outwardly facing, semi-cylindrical flange 25—26 respectively. 27 and 28 indicate leaf strips, 105 which are so formed as to have a hinged connection along their inner margins with each other, and along their other margins, one to each flange 25 and 26. The leaf strips 27—28 have their outer margins bent 110 transversely to provide semi-cylindrical in-turned flanges 29—30 respectively, which

- bear within the similar flanges 25—26 of the strips 23—24. The inner margin of the strip 28 is inturned or bent similar in form to its outer margin to provide a semi-cylindrical flange 31, which engages between the overhanging inner margin 32 of the strip 27 and a suitable curved strip 33 fixed to the under side of said strip 27 adjacent said margin 32. The free margin of the strip 33 is bent to provide a radial flange 34 which is engaged by the edge of the flange 31 to limit and stop the same in the upward swinging movement of the sections 13 and 14.
15. Inclosing and engaging upon the hinge leaf strips 27 and 28, is a ridge cap or piece 35. This cap is made of any desired flexible waterproof material such as, soft sheet lead or copper, or even a good quality of prepared roofing. The margins 36 of said ridge strip are tucked in between the angle bars 15, and the adjacent end margins of the panels 18. To prevent any undue abrasion or wear upon the margins 36 of the ridge cap, by reason of their tucked in position with respect to the panels, I interpose a wear strip 37 between said margins, said wear strip also acting to provide a watertight connection at this point.
30. When the sections 13 and 14 are swinging from the closed position shown in Fig. 1 to the open position shown in Fig. 2, the inner connected together margins of the hinge leaf strips 27—28 will move upwardly under the action of the foreshortening of the distance between the outer margins 29—30 of said hinge strips and carry with it the middle portion of the ridge cap or strip 35 and support the same from beneath so that it
40. can not sag or warp under its own weight or under the action of climatic changes. When the said sections are again being swung into their closed position, the action of the hinge strips will be the reverse.
45. It is apparent that with the one piece ridge cap or strip as described, all seams and cracks, through which rain, wind or snow would enter, are entirely eliminated. The said ridge cap is supported at all times
50. from beneath by means which accommodates for the swinging movement of the sections 13 and 14, so that the ridge piece can not sag or warp, in the movement imparted to it in the opening and closing of said sections.
55. While in describing my invention I have referred to certain details of mechanical construction and form of parts, I do not wish to be limited thereto except as may be pointed out in the appended claims.

I claim as my invention:—

1. A ridge construction of the kind described, comprising in combination with a swinging section, a second section, a flexible

ridge strip connected at its margins to the 65 margins of said sections, and means carried by said sections for supporting said ridge strip from beneath in all positions of said swinging section.

2. A ridge construction of the kind described 70 comprising in combination with two sections adapted to swing about a common horizontal axis, a flexible ridge strip connected at its margins to the adjacent margins of said sections, and members hingedly 75 connected to each section and to each other, and acting to support said ridge strip from beneath in all positions of said swinging sections.

3. A ridge construction of the kind described 80 comprising in combination with two sections adapted to swing about a common horizontal axis, a flexible ridge strip connected at its margins to the adjacent margins of said sections, sheet metal strips 85 hingedly connected to each section, and to each other, and acting to support the ridge strip from beneath in all positions of said swinging sections.

4. A ridge construction of the kind described, comprising in a combination with two sections adapted to swing about a common horizontal axis, said sections each including an angle bar along the adjacent margins thereof, a hinge strip fixed to each 95 angle bar, and leaf strips each connected at one margin to each of said hinge strips and hingedly connected at their other margins to each other, said leaf strips being adapted for movement with said sections and having supporting engagement with said flexible ridge strip from beneath to support said ridge strip in all positions of said swinging sections.

5. A ridge construction of the kind described, comprising in combination with two sections adapted to swing about a common horizontal axis, said sections each including an angle bar along the adjacent margins thereof, a hinge strip fixed to each 10 angle bar and having a curled marginal flange, and leaf strips having curled marginal outer flanges hingedly engaged in the marginal flanges of said strips on the angle bars, said leaf strips having inner marginal 11 flanges which are hingedly connected together, said leaf strips moving with the sections and supporting the ridge strip from beneath, in all positions of said swinging sections.

In testimony that I claim the foregoing as my invention, I affix my signature in the presence of two witnesses, this 24th day of November, A. D. 1920.

JOSEPH SYLVAN.
